(57) **CLAIM**

The ornamental design for a coreless inductor magnetic stripe simulacrum for right angle transaction acceptance systems, as shown and described.

DESCRIPTION

FIG. 1 is a perspective view of a first side of a coreless inductor magnetic stripe simulacrum for right angle transaction acceptance systems showing my new design;

FIG. 2 is another side perspective view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front elevational view thereof; and,

FIG. 8 is a rear elevational view thereof.

The broken line showing the environment is for illustrative purpose only and forms not part of the claimed design.
